SAFETY LOWERING DEVICE

George P. Kimmel, Brookeville, Md.

Application June 3, 1940, Serial No. 338,643

5 Claims. (Cl. 244—138)

This invention relates to an armor piercing projectile plane.

The invention hereinafter described is constructed on the principle of aiming a weapon at the target or objective so as to make each shot count, as distinguished from the well known method of general distribution of shot, shell and bomb over a specified area in the hope that one or more may hit a vulnerable spot. The invention hereinafter described, instead of depending upon preferably one aerial bomb or torpedo out of a vast number striking a ship or objective to sink or damage the objective, aims to provide a weapon which may be aimed directly at the objective and which is provided with means whereby the projectile will be more effective and in the long run will be less expensive than where a large number of bombs or torpedoes are discharged with the hope that one or more of them will reach the particular objective.

In the invention to be hereinafter described, a twin-motor plane is used having the fuselage point constructed of a large calibre explosive shell provided with a time fuse so that the explosion of the shell will occur after the shell has pierced the deck armor of a battleship or other objective. This shell may be a fourteen or sixteen inch shell or larger with the main part of the fuselage enclosing the pilot and to which is also attached the escape mechanism by means of which the pilot may leave the plane sufficiently in advance of the time the shell or projectile strikes the objective so as to be a safe distance away from the explosion.

The escape mechanism includes a detachable parachute and in one instance includes the rear or tail of the plane which latter part is formed of buoyant material so as to form a raft to be used by the pilot when landing on water. The parachute with the floating combined raft and rudder is automatically released and is instantly opened at a predetermined distance away from the objective which may be determined by the pilot.

An object of this invention consists of shooting or diving of a plane in a direct and substantially vertical line and at a speed so great that when the plane and its projectile nose strikes the deck of a battleship or other objective, there will be no question of penetration, no question of the explosion of the projectile within the objective and no question of the total destruction of the objective instead of merely temporarily putting the objective out of commission or action.

Another object of this invention is to provide a powered projectile which is so constructed that

it may be flown to an objective, aimed or pointed at the objective, and the operator or pilot released therefrom without changing the flight of the projectile.

5 A further object of this invention is to provide a powered projectile which is formed with armor piercing characteristics and which is capable of being accurately aimed at an objective.

A still further object of this invention is to provide a powered projectile which is formed with supporting wings and power means carried by the wings, the power means being manually controlled or regulated from a position rearwardly of the projectile.

15 A further object of this invention is to provide a dive projectile having an airplane body and guide structure together with an improved escape means for the pilot or operator so that the pilot or operator will be automatically ejected or pulled out of the fuselage by an escape mechanism which is manually controlled by the pilot or operator.

A further object of this invention is to connect an armor piercing projectile to an airplane structure and to so form the airplane structure that a portion thereof will be released from the remaining portion at the time the pilot or operator leaves the airplane, the released portion forming a raft to be used by the pilot or operator when alighting on water.

20 30 A further object of this invention is to form an armor piercing projectile at the forward end of a fuselage, and to cover the rear portion of the fuselage with portions of a parachute, the parachute being attached to the fuselage by a releasable ejecting mechanism which is adapted to at least partially open the parachute prior to the departure of the pilot or operator from the fuselage so as to make certain of the opening of the parachute.

35 40 A further object of this invention is to provide a combined airplane and projectile and an escape parachute which has the shrouds thereof connected to the pilot's seat, the airplane being formed with a fuselage having an escape track which is operable to force the pilot laterally of the fuselage at the time the pilot leaves the fuselage.

45 50 A further object of this invention is to provide in a flying armored piercing projectile structure, a manually releasable escape mechanism initially operable by the pilot or operator so that the projectile may be aimed at the objective, the power controls set or locked and the pilot or operator forcibly ejected from the fuselage.

55 A further object of this invention is to provide

in a powered flying projectile, a separable, buoyant tail part secured to a parachute so that the tail part will float on water and form a raft, the release of the tail part also assuring the release of the parachute and preventing entanglement of the parachute shrouds with the rear of the fuselage.

To the foregoing objects and to others which may hereinafter appear, the invention consists of the novel construction, combination and arrangement of parts as will be more specifically referred to and illustrated in the accompanying drawings wherein are shown embodiments of the invention, but it is to be understood that changes, variations and modifications may be resorted to which fall within the scope of the invention as claimed.

In the drawings—

Figure 1 is a perspective view partly broken away and in section of an armor piercing projectile plane constructed according to an embodiment of this invention, the plane being shown in a vertical or diving position.

Figure 14 is a fragmentary sectional view taken on the line 14—14 of Figure 13.

Figure 15 is a fragmentary side elevation of the rear portion of the fuselage.

Figure 16 is a fragmentary sectional view taken on the line 16—16 of Figure 13.

Referring to the drawings and first to Figures 1 to 10, inclusive, numeral 10 designates generally the fuselage of a plane constructed according to an embodiment of this invention and the numeral 11 designates generally a projectile which is formed with the fuselage 10 and projects forwardly thereof in axial alignment with the axis of the fuselage 10. The fuselage 10 has secured thereto a pair of laterally projecting wings W, and a pair of motors M are carried by the wings W on opposite sides of the projectile 11. The motors M have connected therewith propellers P for propelling the plane to the desired objective.

The projectile 11 comprises a shell 12 which has mounted therein an explosive charge 13. The forward or nose portion of the projectile 11 is formed with a solid body or nose 14 having a charge firing cap 15 mounted on the terminal end thereof. The charge firing cap 15 is adapted to be connected to the charge 13 in a conventional manner so that when the cap 15 strikes the ob-

jective, the charge 13 will at the proper time be exploded by the firing charge which extends through the body 14. At the rear of the projectile 11, the fuselage 10 is formed with a pilot chamber and is provided with a cowl which is partly enclosed by a top wall 16 of transparent material and a front wall 17 which is inclined rearwardly and upwardly from the upper surface of the fuselage 10.

The cowl formed by the transparent members 16 and 17 engages over the pilot chamber 18 in which a pilot seat 19 is positioned. The pilot chamber 18 at the rear thereof is formed with an opening 20, the purpose for which will be hereinafter described.

A plurality of radially arranged projectile and plane guiding fins 21 are carried by the fuselage 10 and are disposed about the pilot chamber 18. The fins 21 are of suitable length and width so that when the pilot leaves the plane and locks the controls thereof, the fins 21 will coat with the locked controls in guiding the plane and projectile toward the objective. The fuselage 10 comprises a substantially solid part 22 enclosing the pilot chamber 18, the upper portion of which is formed with the opening 20. The rear or tail portion of the fuselage 10 comprises a plurality of rearwardly extending skeleton frame members or strips 23 which are secured at their forward ends to the body portion 20 and extend rearwardly thereof in tapering relation so as to form a rearwardly reducing tail part.

The skeleton frame strips 23 rearwardly of the body 20 are secured together by means of a plurality of arcuate connecting members or braces 24 which extend inwardly of the frame structure so as to provide longitudinal channels 25, the purpose for which will be hereinafter described. At their rear ends, the longitudinal strips 23 are secured to an annular ring 26, the strips 23 being welded or otherwise fixedly secured to the ring 26. A parachute structure generally designated as 27 is adapted to encompass or enclose the skeleton tail part of the fuselage 10 which is formed by the longitudinal strips 23 and the connecting strips 24 and the parachute 27 is so folded that the loose portions 28 thereof may engage in the channel members 24. The remaining portions of the parachute 27 are adapted to be stretched between the frame members 23 so as to form a substantially solid or smooth wall enclosing the skeleton tail part of the fuselage 10.

The parachute 27 in the present instance is provided on the exterior surface thereof with a plurality of yieldable bands or strips 29 which are secured to the exterior of the parachute 27 in any suitable manner and these strips 29 are adapted to extend lengthwise of the fuselage 10 and also provide a means for firmly holding the cover of the parachute against the skeleton frame structure. The strips 29 are of resilient construction so that when the parachute opens, these strips may bend longitudinally and in this manner hold the parachute from collapsing or from undue tearing.

The body 22 at the rear thereof has secured thereto a pair of parachute opening springs 30 which in Figure 9 are shown in open position. These springs 30 when the parachute 27 is in inoperative position, are contracted to the position shown in Figure 6. The skeleton frame members 23 at a point rearwardly from the fuselage body member 22, have formed therewith abutments or detents 31 over which the parachute 27 is adapted to engage. The forward or open end of the parachute 27 is held in tight position about the for-

ward ends of the frame members 23 by means of a forward split clamping band.

The clamping band 32 engages about the strips 29 of the parachute 27 and also the fabric forming the parachute and the rear edge of the clamping band 23 is adapted to engage against the abutments 31 so that the band 32 will not slip rearwardly under vibration or the like. The free ends of the band 32 are formed with band locking ears 34 and 35 which are provided with openings 36 and 37 relatively. A band locking member 38 engages through the openings 36 and 37 and is adapted to tightly hold the band 32 about the parachute and about the skeleton frame structure formed by the longitudinal strips 23. The locking member 38 extends lengthwise of the fuselage 10, and, as will be hereinafter described, is adapted to be moved forwardly to a band releasing position.

A plurality of intermediate clamping bands 39, 40 and 41 are mounted about the parachute 27 and are constructed similar to the band 23, the band 39 having ears 42 and 43 which are held in locked position by means of a releasable locking member 44. The band 40 is provided with a pair of ears 45 and 46 which are held in locking position by means of a locking member 47. The band 41 is provided with a pair of ears 48 and 49 which are held together by means of a locking member 50. An elongated releasing rod 51 is secured to the locking members 38, 44, 47 and 50 and extends beneath the fuselage 10, terminating at a point forwardly of the rear end of the body part 22.

A releasing lever 52 is pivotally mounted on a pivot 53 carried by a notched or toothed plate 54 which is mounted within the pilot compartment 18. The lever 52 is provided with a spring pressed latching dog 55 which is connected to a dog releasing lever 56 carried by the upper end of the lever 52. The dog 55 is adapted to engage in a selected notch 57 carried by the plate or rack 54 so as to hold the lever 52 in a normally band locking position. The forward end of the rod 51 is connected to the lower end of the lever 52 being connected to the lever 52 by a connector 58 which is slidably in a slot 59. The lever 52 at its lower end extends through an opening 60 which is formed in the bottom of the body 22.

The shrouds 61 of the parachute 27 are secured to the pilot seat 19, the shrouds 61 being connected to fastening devices 62 which are fixed to the seat 19 in such a manner that when the parachute 27 is released from the fuselage 10, the seat 19 will be maintained in a normal upright position. The legs 63 of the seat 19 are each formed with openings 64 through which seat locking members 65 engage. The locking members 65 are connected to the rod 51 by means of connecting members 66 which may be integral with the locking members 65. The locking members 65 and the connecting members 66 may be constructed in the form of an L-shaped locking structure having one leg 65 thereof engaging in the openings 64 of the legs 63 and the legs 66 may be extended through openings 67 formed in the body 22.

A rear clamping band 68 engages about the parachute 27 and the bands 29 and the rear clamping band 68 is provided with a pair of ears 69 and 70. A locking member 71 engages through the ears 69 and 70 and is fixed to the releasing rod 50. In practice the locking members 44, 47, 50 and 71 are constructed of such a length that these locking members are disengaged from the clamping members in progression from the rear 75

toward the front so that when the foremost band locking member 38 is released so as to permit the parachute opening springs 30 to open the parachute, there will not be any band rearwardly of the forward band 32 which will prevent the instantaneous opening of the parachute.

A tail structure 72 is carried by the rear end of the fuselage 10 and this tail structure 72 comprises a substantially stationary forward body part 73 and elevators 74 which are pivotally connected to the rear of the body part 73. The elevators 74 are operated by conventional operating means extending through the fuselage and the tail structure 72 also includes one or more rudders 75 which are pivotally mounted on the body part 73. The rudders 75 are adapted to be operated in the conventional manner and preferably by releasable means so that when the tail structure 75 is released from the fuselage by opening of the parachute 27, the operating connections to the tail structure 72 will also be disconnected.

The tail structure 72 is detachably connected to the fuselage 10 by means of a plurality of spring arms 76 which are fixed to the body part 73. The spring arms 76 at their forward ends engage about the rear part of the fuselage 10 and are formed with releasable hooks or lugs 77. The bands 29 of the parachute are each formed with a detent or lug 78 which is adapted to be engaged by the hook or locking member 77 so as to detachably lock the spring fingers 76 on the rear of the fuselage 10. The rear ends of the parachute reinforcing members 29 are connected to a plate 79 which forms the top of the parachute 27 and the forward end of the tail member 72 may be connected to the plate 79 by means of connecting members 80. The body part 73 of the tail member 72 is preferably hollow for at least a portion thereof so that the tail member 72 will be buoyant. A pilot parachute 81 is disposed within the body part 73 of the tail 72 and preferably the body part 73 is provided with a spring pressed closure 82 through which the pilot parachute 81 is adapted to be ejected.

A pilot parachute ejecting spring 83 is disposed within the body 73 and the rear end of the spring 83 has secured thereto a follower or plate 84. The forward end of the spring 83 engages against a plate or abutment 85 formed in the body 73 as shown in Figure 5. The spring 83 is held in a compressed position by means of a pivoted locking member 86 which is mounted on a pivot 87. The locking member 85 has one portion thereof projecting within the body part 73 and is adapted to engage against the rear side of the follower 84. The projecting portion of the locking member 86 is provided with an opening 88 through which a locking member 89 engages. The locking member 89 is formed in substantially L-shape with one leg 90 thereof extending at right angles from the body 73 and this leg 90 is connected to the rear end of the releasing rod 51.

The tension of the spring 83 tends to hold the projecting end of the locking member 86 against the angle formed between the two parts 89 and 90 of the locking member and preferably the locking part 89 is substantially shorter in length than the locking member 86 so that the locking member 89 will be released before the locking member 86 is released from the band ears 69 and 70.

In order to provide a means whereby the pilot seat 19 may be discharged from the fuselage 10 in a lateral direction, I have provided a pair of seat guiding tracks 91 which are secured to the

frame members 23 and extend rearwardly and upwardly. When the parachute 27 opens and the shrouds 61 pull the seat 19 rearwardly, the seat 19 with the pilot strapped thereto will be pulled rearwardly and outwardly of the skeleton tail part of the fuselage 10 so that the shrouds 61 will not become entangled in any part of the fuselage and so that the pilot seat with the pilot strapped thereto will be pulled clear of the fuselage.

The tracks 91 may be supported by means of supporting bars 92 and 93 which extend transversely across the skeleton of the fuselage, the track supporting members 92 and 93 being fixed to pairs of frame members 23.

Referring now to Figures 11 to 16, inclusive, there is disclosed herein a modified form of this invention which is adapted for use on land objectives. An armor-piercing projectile 94 is formed at the forward end of a fuselage 95 and the projectile 94 comprises a hollow body 96 having a solid nose 97 terminating in a firing cap 98. A charge 99 is disposed in the body 96 and a rear wall 100 is connected to the body 96 and is of such a construction that it may be removed for the purpose of inserting the explosive charge 99. A pair of wings 101 are carried by the fuselage 95 and partly by the projectile body 96 and a pair of motors 102 are carried one by each wing 101. The motors 102 are controlled by suitable controlling devices extending into the pilot chamber 103 formed in the fuselage 95. A tail structure 104 is carried by the rear of the fuselage 95 and elevators 105 are pivotally carried by the rear of the stationary part 106 of the tail structure 104. A depending rudder structure 107 is carried by the tail structure 104 and it will be understood that the pivoted part 108 of the tail structure 107 and the elevators 105 are connected in a conventional manner to control devices extended into the pilot chamber 103.

A parachute housing 109 is carried by the fuselage 95 and in the present instance the housing 109 is substantially elliptical in transverse section and is inclined upwardly and rearwardly and opens through the upper side of the fuselage 95. A closure plate 110 engages the upper open end of the housing 109 and is releasably held in the open upper end of the housing 109 by means of a plurality of clamping members 111.

The clamping members 111 are in the form of spring clips which are fixed to the closure 110 and normally hold the closure 110 in an operative position to close the upper end of the housing 109. A parachute 112 is mounted in the housing 109 and the shrouds 113 of the parachute 112 are extended through an upwardly opening slot 114 formed in the housing 109 on the forward side thereof. A supporting plate 115 is carried by the forward side of the housing 109 so as to support the shrouds 113 in their extended position through the slot 114. The shrouds 113 are connected to fastening devices 116 which are secured to a pilot seat 117 positioned within the chamber 103. The fuselage 95 is formed with an elongated opening 118 in the upper side thereof through which the pilot seat 117 with the pilot strapped thereto is adapted to be pulled. A pair of longitudinal arcuate chair guiding tracks 119 are carried by the fuselage 95 and extend upwardly and rearwardly. These tracks 119 are preferably of substantially U-shape in transverse section and the legs 120 and 121 of the seat 117 loosely engage within the channel track members 119. Each track member 119 at its forward or inner end is formed with

a stop member 122 having a rearwardly projecting lug 123 formed therewith which is adapted to engage in a slot 124 formed in the forward sides of the front legs 120. The rear legs 121 are substantially shorter in length than the front legs 120 so that the seat 117 will be disposed in a normal upright position when the seat 117 is in its normal position.

The parachute 112 is adapted to be ejected 10 from the housing 109 by means of an expansive spring or charge member 125 which is disposed in the housing 109. One end of the spring 125 bears against the inner wall or bottom 126 of the housing 109 and a follower or cap 127 engages the other or upper end of the spring 125. The cap or follower 127 is slidable in the housing 109 and bears against the parachute 112. The spring 125 is held in a compressed position by means of a pivoted latch member 128 which is mounted on a pivot 129. The pivot 129 extends through a pair of ears 130 carried by the forward side of the housing 109 and the bill of the latch member 128 is adapted to engage in an opening 131 formed in the forward side of the housing 109.

The latch member 128 engages against the upper side of the follower 127 so as to normally hold the spring 125 in a compressed position. A spring 132 is interposed between the housing 109 and the latch releasing lever 133 which is formed with the latch 128 so as to constantly and yieldably hold the latch 128 in a locked position.

A latch releasing lever 134 is pivotally mounted on a pivot 135 carried by a bearing 136 which is fixed to the fuselage 95. The releasing lever 134 is connected to the latch lever 133 by means of a connecting link 137. The releasing lever 134 is held in a latch locking position by means of a toothed rack or quadrant 138, the lever 134 having a spring pressed pawl 139 connected to a pawl releasing lever 140. The pawl 139 is adapted to engage the quadrant 138 and thus hold the lever 134 in a latch locking position.

In order to provide a means whereby the seat 117 may be held in a fixed or locked position, and whereby the seat 117 may be released when the latch 128 is released, I have provided a pair of pivoted seat locking arms 140 which are pivotally carried by bearings 141 fixed to the fuselage 95. The seat locking arms 140 are spring pressed to a released position by means of a spring 142. The seat locking arms 140 are adapted to engage in a notch 143 of a rear leg 121 and the locking arms 140 are held in locked position by means of a right angularly disposed bar 144 which is fixed to the link 137. In the present instance the bar 144 is connected to the link 137 by means of a connecting member 145 which extends upwardly from the link 137. When the releasing lever 134 is in a latch locking position, the bar 144 will be in the position shown in Figures 12 and 13 and in this position the seat locking levers or arms 140 will be engaged in the notches or keepers 143.

The bar 144 will constantly press the seat 117 forwardly but the forward tilting of the seat 117 is prevented by engagement of the seat locking levers 140 in the notches 143.

In order to provide a means whereby the shrouds 113 and the parachute 112 will not become entangled with the tail structure 104, I have provided a plurality of guard members 145 in the form of tensioned wires or rods which are connected at their forward ends to the fuselage 95 and are connected at their rear ends to the upper surface of the stationary tail part 106. These guard members 145 form a screen about

the upper part of the tail structure 104 so that the shrouds 113 will not become entangled with the tail structure 104.

The fuselage 95 is provided with a transparent connector 146 formed by an upwardly and rearwardly inclined front wall 147 and a hood 148 also of transparent construction. The rear portion of the cowl 146 is preferably open so that when the seat 117 is released and moves rearwardly and upwardly, the cowl 146 will not impede the movement of the seat 117. A sighting member or telescope 149 is fixed by a mounting 150 to the fuselage 95 on the upper side thereof and the sighting member 149 is disposed in a position with the longitudinal axis thereof parallel with the longitudinal axis of the fuselage 95 and the projectile 94.

In the use and operation of this weapon shown in Figures 1 to 10, inclusive, the plane structure will be operated in a conventional manner by the pilot strapped to the seat 19. When the pilot nears the objective which in the present instance may be a floating objective such as a battleship or the like, the pilot will sight the projectile 11 through a sighting member 151 which is carried by the cowl 16-17. The plane is disposed in either a vertical diving position or a diving position inclined to the vertical and the pilot initially locks the normal controlling mechanism for the plane and operates the motors M at their fullest speed so that the plane will be moving at the highest possible speed.

With the controls for the motors M and the plane operating structure locked, the pilot pulls the parachute releasing lever 52 rearwardly to its released position. Rearward movement of the lever 52 will pull the releasing rod 51 forwardly and progressively release the parachute clamping bands 68, 41, 40, 39 and 32 and will also release the parachute locking lever 86. When the parachute locking lever 86 is released, the spring 83 will expand and force the parachute 81 outwardly of the tail member 73, swinging the spring pressed closure 82 to an open position. The shrouds 152 of the parachute 81 are connected to the body part 73 so that the small parachute 81 will substantially support the tail part 72 above the main parachute 27.

When the foremost parachute clamping band 32 has been released, the parachute opening members 30 will raise the forward open end of the parachute 27 to permit the air to enter within the parachute 27 and thus pull the parachute 27 from the skeleton fuselage members 23. As the parachute 27 tightens on the shrouds 61, these shrouds will pull the seat 19 rearwardly and laterally along the tracks 91 so that the pilot will be supported from the parachute 27.

The parachute clamping bands 32, 39, 40, 41 and 68 may drop on the ground or in the water, these bands being of such resiliency that as soon as they are released they will snap away from the parachute 27. As the motors M of the plane are at this time operating at their full speed and the ailerons are locked relative to the wings W, the main body of the plane will move in a substantially straight line toward the objective.

In order to assist in maintaining the plane in a straight line, the fins 21 will be active, the fins 21 serving as a supplemental fixed rudder structure for guiding the projectile 11 and the plane toward the objective.

When the projectile 11 strikes the objective, the projectile will pierce the objective and the charge 13 will explode after the piercing of the

objective through the charge firing mechanism connected to the cap 15. As the pilot has left the plane and is floating downwardly with a parachute 27, the pilot will have a fair chance of surviving after the explosion of the projectile 11. The tail structure 72 being formed of buoyant material may be used by the pilot in floating on the water.

Where the structure shown in Figures 11 to 16 is used, the pilot will point the projectile 94 toward the objective and lock the controls for the motors 102 and the controls for the rudder structure 104 together with the conventional ailerons or other controls. The projectile 94 will be pointed directly at the objective which will be sighted through the sighting member 149. After the controls for the airplane have been locked, the pilot may pull the releasing lever 104 rearwardly so as to release the spring 125 from the latch 128.

Release of the spring 125 will permit this spring to expand and force the closure 110 from the upper end of the parachute housing 109. At the same time the parachute 112 will be ejected from the housing 109 and with the opening of the parachute 112, the pilot seat 117 will be pulled from the fuselage 95. At the same time that the latch 128 is moved to a released position, the seat locking arms 140 are released by rearward movement of the locking bar 144 thus permitting the spring pressed locking levers 140 to swing rearwardly to a released position. When the parachute 112 opens the seat 117 is pulled outwardly and upwardly along the tracks 119 and the guard members 145 will prevent any of the shrouds 113 from becoming entangled with the rudder or tail structure 104.

With a weapon constructed according to this invention, the objective can be hit more accurately than where a bomb or torpedo is released from a bombing plane and permitted to gravitantly drop downwardly onto the objective. With a structure of this kind, the projectile is pointed at and moving downwardly in the direction of the objective before the pilot leaves the plane and as the controls for the plane are locked, the plane will not vary in its direction toward the objective. As the objective for a weapon of this type has a value far greater than the cost of this weapon, the use of this weapon in destroying the objective will not be out of proportion to the results obtained thereby.

In order to provide a means whereby the wings W or 101 may be released from the projectile, a suitable shear may be placed adjacent each bolt securing the wings to the projectile and fuselage so that the initial impact of the projectile will cut the bolts and release the wings from the projectile. In this manner the wings will not impede the piercing of the objective by the projectile. This same result may also be obtained by providing frangible bolts wherever practicable.

What I claim is:

1. In a plane structure including a fuselage and wings; said fuselage including a skeleton rear portion, a combined skeleton cover and parachute, means releasably holding said cover and parachute on said skeleton rear portion, a manual operator connected to said holding means, a buoyant member connected to said parachute and operatively connected with said holding means, a supplemental parachute carried by said buoyant member, and means for

releasing said supplemental parachute coincident with the release of said parachute.

2. In a plane structure including a fuselage and wings; said fuselage including a skeleton rear portion, a combined skeleton cover and parachute, means releasably holding said cover and parachute on said skeleton rear portion, a manual operator connected to said holding means; a buoyant member connected to said parachute and operatively connected with said holding means, a supplemental parachute carried by said buoyant member, an ejector for said supplemental parachute, and means connected with said holding means for rendering said ejector active upon release of said holding means.

3. In a plane structure including wings and a fuselage; said fuselage including a skeleton rear portion, a combined parachute and cover about said skeleton rear portion, circular resilient split clamping bands holding said parachute about the outer side of said skeleton rear portion, a locking member connecting the ends of each band, an elongated member connected to said locking members, a manual operator connected to said elongated member, resilient parachute opening means carried by said fuselage and normally held in compressed position by certain of said bands, a pilot seat track in said fuselage, a pilot seat on said track connected to said parachute, locking means for locking said seat relative to said

track, and means connecting said locking means with said operator.

4. In an aircraft having wings and a power means carried by said wings, a skeleton fuselage, a parachute substantially enclosing at least a portion of said fuselage, a pilot seat connected to said parachute, releasable holding means for holding said parachute on said fuselage, a hollow buoyant tail assembly releasably secured to said fuselage, a parachute for said tail assembly, and means connected with said holding means for releasing said second parachute coincident with said first parachute.

5. In an aircraft having a fuselage and wings, power means carried by said wings, a detachable hollow buoyant tail structure at the rear of said fuselage, a parachute at least partially enclosing said fuselage, releasable clamping means holding said parachute and said tail structure on said fuselage, a pilot seat connected to said parachute, means releasably holding said seat in said fuselage, said clamping means including forwardly projecting resilient hook members carried by said tail, keeper means carried by said fuselage, and a split clamping band holding said hook members in engagement with said keeper means, and a single releasing mechanism for said clamping means and said seat holding means.
